UNITED STATES PATENT OFFICE.

WILLIAM S. ROATH, OF AKRON, OHIO.

DIRECT-RETURN VALVE FOR STEAM-HEATING SYSTEMS.

1,268,280.

Specification of Letters Patent. Patented June 4, 1918.

Application filed May 28, 1917. Serial No. 171,379.

To all whom it may concern:

Be it known that I, WILLIAM S. ROATH, a citizen of the United States, residing at Akron, in the county of Summit and State of Ohio, have invented new and useful Improvements in Direct-Return Valves for Steam-Heating Systems, of which the following is a specification.

This invention relates to improvements in direct return traps for steam heating systems and the object of the invention is to provide a valve arranged for incorporation in a heating system and possessing the function of controlling the return of the water formed by the condensation of the steam in the system to the boiler irrespective of the pressure in the latter.

As is well known it frequently happens that the steam pressure in a heating boiler is so great that proper return drainage of the system is impossible and hence a suitable controlling valve is necessary. More specifically my invention comprises a valve casing in association with a tank or reservoir, the latter in open communication with the drainage pipe of the heating system and with said valve casing. The reservoir contains a float for controlling the operation of the valve. The valve casing is provided with a vent open to the atmosphere when the reservoir is filling. The interior of the casing is also in communication with the main steam line of the system. In the casing is a steam valve and also a vent controlling valve coupled together and arranged to simultaneously be operated by the float, said valves arranged when shifted into one position to open the steam inlet and close the vent opening, said valves arranged when in their other or opposite position to open the vent and close the steam inlet.

Furthermore, the valves are so disposed that when the steam valve is moved to its closed position the pressure of the steam in the system aids and assists the other mechanism in holding the steam valve securely in its seat and in its operative position.

With the foregoing and other objects in view, the invention consists in the novel construction, combination and arrangement of parts constituting the invention to be hereinafter specifically described and illustrated in the accompanying drawings which form a part hereof wherein is shown the preferred embodiment of the invention, but it is to be understood that changes, variations

and modifications can be resorted to which come within the scope of the matter herein-after claimed.

In the drawings in which similar reference numerals indicate like parts in the different figures,

Figure 1 is a view in side elevation and partly in section, of a valve embodying the present invention.

Fig. 2 is a sectional view taken approximately on line 2 of Fig. 1.

Fig. 3 is a sectional view of the valve and its connected mechanism, and

Fig. 4 is a diagrammatic view of a steam heating system, with the valve forming the subject matter of the present invention incorporated therein.

The valve of the present invention is designed for incorporation in a heating system and in Fig. 4 is shown diagrammatically a simple form of heating system to show the connection of the valve with the system.

In the drawings the reference numeral 1 denotes an ordinary heating boiler from which extends a main steam line or pipe 2 from which extends a branch 3 connected to a radiator 4. The connection of the pipe 3 is preferably at one end of the radiator and the opposite and lower end portion of the radiator is provided with a check valve 5 from which leads a drainage pipe 6 connecting with the lower part of the boiler. In the pipe 6 is a check valve 7. Also communicating with the drainage pipe 6 is a branch pipe 8 establishing communication with a reservoir 9 and in this branch pipe is a controlling valve 10. Mounted on the reservoir 9 is a direct return valve 11 and extending between the valve and the main steam line is a pipe 12 provided with a controlling valve 13. From the lower portion of the reservoir 9 extends a pipe 14 communicating with the pipe 6 and provided with a check valve 15.

The device which forms the primary feature of the present invention embodies a reservoir 9 the upper portion of which is provided with a convexed enlargement 17, and with an interiorly threaded boss 18 which receives the lower threaded hollow stem 19 of the valve 11. One wall 20 of the reservoir is provided with a threaded boss 21 to receive the threaded end of the branch pipe 8 leading from the drainage pipe 6. This wall 20 is preferably integral with the main body of the reservoir and the opposite open

end of the reservoir is closed by means of a head 22, held in position by ordinary cap screws or bolts 23 and is adapted to form a hermetically tight union with the end of the 5 reservoir 9. Preferably formed integrally with the head 22 is a hollow bracket 24 provided in one wall near its outer free end with a bearing 25 and in the other wall opposite to the bearing 25 with a threaded opening 10 which receives a packing gland 26 the packing gland and bearing 25 constituting means for supporting a rotatable shaft 27. It may be stated that the interior of the hollow bracket 24 is in open communication with the 15 interior of the reservoir 9. Fixedly mounted on the shaft 27 within the hollow bracket is a hub 28 to which is secured a stem 29 bearing at its outer-end a float 30 so positioned that when moved to its upper position 20 it is received in the enlargement 17 and when moved to its lower position it is positioned near the lower wall of the reservoir 9.

Loosely mounted on the shaft 27 is an arm 31 having an offset portion 32 which constitutes an abutment or lug for a purpose to be later described. Extending upwardly from the offset portion is an integral portion 33 bearing a counterweight 34. The arm 31 also has oppositely disposed arms 35 both of which are arcuately formed and both provided at their ends with lugs 36 having threaded apertures to receive adjusting screws 37. The inner ends of these adjusting screws are disposed a considerable 35 distance apart and the adjusting screws are held in determinate positions by means of locking nuts 38.

Fixedly secured against independent revolution, by means of a key 39, on the shaft 27 40 and outside of the arm 31 is a tappet 40, V-shaped in side elevation and comprising two arms 41 and 42 the outer ends of which are provided with heads 43 provided with threaded apertures to receive adjusting 45 screws 44 and these adjusting screws may be held in determinate positions by locking nuts of ordinary construction. The tappet 40 is adapted to be rocked intermittently whenever the float 30 is raised or lowered 50 and the offset portion 32 or abutment is arranged to lie in the path of movement of the arms 41 and 42 as they oscillate to move the arm 33 and counterweight 34. The oscillation of the arm 33 also oscillates the 55 two arcuate arms 35.

Preferably formed integrally with the head 22 and positioned above the hollow bracket 24 are a pair of complementary brackets 50 through the outer ends of which 60 extends a bolt 51 constituting a pivot for a lever 52, the upper end of which is provided with a head 53 having a suitable aperture to receive a pivot pin 54. The lower end 55 of the lever 52 is arranged to lie in the path 65 of movement of the set screws 37 on the

arcuate arms 35. The valve casing 11 comprises an outer wall or casing 56 approximately cylindrical in cross section and provided in its upper portion with an interiorly threaded upwardly-projecting boss 57 70 to receive the lower threaded end of a vent pipe 58. Below the boss 57 is a chamber 59 provided with end walls 60 and 61. The wall 61 is provided with a valve seat 62 and the other wall with an opening constituting 75 a bearing for a valve stem 63 to be more fully described. The wall 56 of the valve casing is provided as shown, at the right end in Fig. 3, with a projecting chambered boss 64 separated from the interior 65 of 80 the casing by a partition 66 containing an opening provided with a valve seat 67 which is in alignment with the opening 62 in the wall 61. The end wall 68 of the boss is provided with a threaded opening to receive 85 the end of the steam inlet pipe 12. The opposite end of the valve casing 11 formed with a wall 69 containing an interiorly threaded aperture boss 70 arranged to receive a nut 71 which is provided with a 90 threaded opening for the reception of a packing gland 72, for the valve stem 63.

Mounted in the packing gland 72 and the opening in the wall 60 as bearings is a valve stem 63 which comprises two members 73 and 74 in alignment with each other and approximately of equal diameter and of similar conformation. The two are united by providing a threaded central recess in the member 73 and with a projecting 100 complemental threaded stem on the end of the member 74 for coupling the two members of the valve stem 63 together when the threaded stem is screwed into the recess in the member 73. The member 73 is provided 105 with a threaded outer end to which is coupled a bifurcated head 75 through which extends the pivot pin 54 for pivotally coupling the head 75 to the lever 52. The end of the member 74 is provided with a valve 110 76 adapted to seat on the valve seat 67 for closing the passage from the pipe 12 to the interior 64 of the valve casing 11. Positioned on the valve stem 63 and near the point where the two members 73 and 74 are 115 coupled together is a vent valve 87. The position of the two valves 76 and 77 is such that when the steam valve 76 is in its operative or closed position the vent valve 77 is in its inoperative or open position and the 120 reverse of this is true, that is to say, when the vent valve 77 is in its closed position the steam valve 76 is in its open position. For convenience in assembling and dismounting the valve stem 76 is provided with a grooved 125 lug 78 to receive a screw driver for rotating the member 74.

In the operation of the device the products of condensation from the heating system represented by the radiator 4 pass the 130

check valve 5 and by means of the drainage pipe 6 return to the boiler 1 past the check valve 7 under normal conditions, but in case of excessive pressure in the heating system sufficient to prevent the return of the condensed water from the heating system to the boiler recourse is had to the return valve which forms the subject matter of the present invention. The operation of the valve 6 is as follows: Water condensed by the heating system flows on by means of the pipe 8 to the reservoir 9 which is permitted by reason of the fact that the valve 87 is in its open or inoperative position permitting air 10 contained in the reservoir 9 to pass outwardly through the chamber 59 and vent 58. The float 30 is raised by the accumulated water and through its connection with the shaft 27 operates the mechanism for relieving the reservoir of the accumulated water. In the drawings the arm 33 carrying the counterweight 34 is in an almost vertical position with the steam valve 76 in its closed position and with the vent valve in its open 20 position. The pressure of the steam in the pipe 12 tends and assists in keeping the steam valve 76 securely seated on the seat 67 to thereby prevent the pressure of the steam from passing into the interior 65 of the valve casing and from thence to the interior of the reservoir 9. Further accumulation of water in the reservoir 9 raises the float 30 sufficiently to cause the arm 41 of the tappet 40 to force the arm 33 over any dead 30 center and causes it to assume the position indicated in dotted lines in Fig. 3 and indicated by the letter A. This movement or oscillation of the arm 33 causes the arcuate arms 35 to move in unison therewith and 40 causes the proper set screw 37, at the right in Fig. 3, to engage the lower end 55 of the lever 52 and rock it on its pivot 51 thereby moving the vent valve 87 to its closed position and the steam valve 76 to its open position. This movement of the two valves closes the vent from the reservoir 9 through the vent pipe 58 and admits steam from the pipe 12 past the valve seat 67 into the reservoir 9 and the pressure of the steam in the 50 system entering through the pipe 12 forces the water in the reservoir 9 outwardly through the drainage pipe 14 past the check valve 15 into the lower portion of the boiler. When substantially all of the water in the reservoir 9 has been drained therefrom the float 30 will assume approximately the position shown in dotted lines in Fig. 1 and the stem 29 of the valve will assume the position shown in dotted lines in Figs. 1 and 60 3. The downward movement of the float 30 by means of the stem 29 and the shaft 27, will move the tappet 40 to the left in Fig. 1, causing one of the set screws 44 to engage the abutment 32 and shift the position of 65 the arm 33 and counterweight 34 to the position shown in dotted lines and designated by the reference letter C. This movement of the counterweighted arm 33, to the right in Fig. 3, will cause one of the set screws 37 to engage the lower end 55 of the lever 52 and shift it to the position shown in Fig. 3 and thereby close the steam valve 76 and shift the vent valve 87 to its open inoperative position thereby permitting the draigeage of the products of condensation from the system into the reservoir 9 and the water when the reservoir is filled will raise the float 30 to its operative position to thereby again oscillate the lever 33 and shift the valves as has been heretofore described. It will be pointed out that when the water in the reservoir has reached approximately the level shown in Fig. 1 the counterweighted lever 33 is almost perpendicular and any further increase of water in the reservoir 70 75 80 85 90 95 100 105 110 115 120 125 130

will raise the float 30 sufficiently to cause the arm 41 of the tappet 40 to shift, to the right in Fig. 1, and force the counterweighted arm 33 past a vertical dead center allowing it to fall to the right and into the position indicated in dotted lines and designated by the letter A. In order to assemble or to dismantle the valve mechanism contained in the casing 56, the pipe 12 and the nut 71 are removed and a screw driver applied to the 100 105 110 115 120 125 130

lug 78 and the two members 73 and 74 are disconnected by revolving the latter after which the member 74 may be withdrawn through the opening containing the end of the pipe 12 and the member 73 carrying the valve 87 is removed through the opening closed by the nut 71 so that easy means are afforded for assembling the valve or for dismantling the same for any purpose.

I claim:

1. A direct return valve for a steam heating system comprising a reservoir connected with the drainage pipe of said system and provided with a pipe leading to the boiler, a valve casing in open communication with said reservoir, said valve casing provided with an inlet for steam under pressure and a vent, a hollow bracket projecting from said reservoir and in open communication with the interior thereof, a rotatable member mounted in the outer end of said bracket, a float in said reservoir, a stem on said float connected with said rotatable member, a weighted arm loosely mounted on said rotatable member, a V-shaped tappet rigidly mounted on said rotatable member and disposed so that the furcations thereof alternately engage said arm for oscillating the same in direct response to the vertical oscillations of said float, a valve stem mounted in said valve casing, valves on said stem for alternately closing the steam inlet and vent opening whereby when one is closed the other is open, a second bracket on said reservoir, a lever fulcrumed on said bracket, one

end of said lever pivotally connected with said valve stem and the other end positioned in the path of movement of the arms carried by said weighted arm and arranged to be alternately engaged thereby, whereby when said weighted lever is oscillated by the movement of said float, said lever is shifted in a reverse direction.

2. A direct return valve for a steam heating system comprising a reservoir connected with the drainage pipe of said system and provided with a pipe leading to the boiler, a valve casing in open communication with said reservoir, said valve casing provided with an inlet for steam under pressure and a vent, a hollow bracket projecting from said reservoir and in open communication with the interior thereof, a rotatable member mounted in the outer end of said bracket, a float in said reservoir, a stem on said float connected with said rotatable member, a weighted arm loosely mounted on said rotatable member, a V-shaped tappet rigidly

mounted on said rotatable member and disposed so that the furcations thereof alternately engage said arm for oscillating the same in direct response to the vertical oscillations of said float, a valve stem mounted in said valve casing, valves on said stem for alternately closing the steam inlet and vent opening whereby when one is closed the other is open, a pair of oppositely disposed arms on said counter-weighted arm, a second bracket on said reservoir, a lever fulcrumed on said bracket, one end of said lever pivotally connected with said valve stem and the other end positioned in the path of movement of the arms carried by said weighted arm and arranged to be alternately engaged thereby, whereby when said weighted arm is oscillated by the movement of said float, said lever is shifted in a reverse direction.

In testimony whereof I have hereunto set my hand.

WILLIAM S. ROATH.
